FILM PROCESSING TANK

William E. Naylor and Lawrence R. Fink, New York, N. Y., assignors to Fink-Roselieve Co. Inc., New York, N. Y., a corporation of New York

Application May 18, 1939, Serial No. 274,331

4 Claims. (Cl. 95—90.5)

Our invention relates to receptacles for processing film, and particularly roll or strip film, as something different from film plates, cut film or film packs. Receptacles of this type are commonly referred to as "tanks," and the main object of our invention is the provision of a tank which is simple, of sturdy construction, easily assembled and operated, and of small cubic capacity.

A further object of our invention is the provision of a tank having a cover which comprises a plurality of light-tight interfitting members.

A further object of our invention is the provision of a tank having a cover which comprises a plurality of light-tight interfitting members, one of which is part of the film supporting component, or reel, disposed within the tank.

A still further object of our invention is the provision of a film supporting reel which comprises a shaft and a plurality of film discs movably mounted thereon.

A still further object of our invention is the provision of a film supporting reel comprising a shaft, a plurality of film receiving discs, and cooperating means on the shaft to align the discs and secure same in spaced apart relationship as desired.

A still further object of our invention is the provision of a film supporting reel comprising a shaft, a predetermined number of horizontal recesses thereon, a plurality of film discs and means projecting therefrom, fitting within the recesses, to secure the discs to the shaft in a plurality of predetermined positions.

Other objects of our invention will in part be obvious and in part pointed out specifically in connection with the following description of an illustrative embodiment.

In the drawing annexed hereto and made a part hereof,

Figure 1 is a vertical section through one form of tank constructed according to and embodying our invention, with parts thereof shown in elevation;

Fig. 2 is a perspective view of the shaft portion of the film supporting component of our device;

Fig. 3 is a perspective view of one of the disc portions;

Fig. 4 is a vertical section on the line 4—4 of Fig. 1; and

Fig. 5 is a horizontal section through the shaft on the line 5—5 of Fig. 2.

Reference numeral 10 indicates the tank of our invention generally, which comprises casing 12, cover 14 and the film supporting reel 16. Casing 12 is preferably circular. The upper portion of the casing wall 13 is provided with an annular channel 15 therein, Fig. 1. Floor 18 is provided with a centrally located upstanding

circular stud 20, which is surrounded by a lower discontinuous circular wall 22.

The closure for our new and improved tank invention comprises in part cover 14 and in part 5 a portion of the film supporting reel 16. Referring specifically to Fig. 1, it will be seen that our cover 14 is of such annular ring shape as to fit on to casing 12, and the outer margins of the cover have formed thereon a pair of concentric downwardly depending spaced flanges 24, 26 which interfit with the channeled top of casing wall 13 in a light-tight manner. If desired, cover 14 may fit onto casing 12 so as to revolve freely thereon, but we prefer to force fit cover 14 15 onto the tank so that same cannot revolve. This is done to reduce the possibility of inadvertently removing the cover during the processing operations, and because agitation of the film supporting reel is otherwise secured. The upper portion of cover 14 is raised, as at 17, and a funnel 19 provided thereon, with a large central opening 21. Opening 21 in the neck of the funnel is defined by a downwardly depending wall 23, and a second and concentric wall 25, spaced 20 from and surrounding wall 23, is provided on the underside of the funnel 19.

The film supporting component 16 of our invention comprises a shaft 30 which has formed therein a central circular bore 32 extending the 30 full length thereof. The upper portion 34 of shaft 30 is preferably circular in cross-section, and is tapered near the top thereof, as at 36. A circular platform portion 40 formed integral with the shaft 30, extending outwardly therefrom at the base of the circular portion 34. Platform 40 is slightly inclined downwardly and outwardly, as seen at 42, Fig. 1, and it is provided with a pair of upstanding concentric discontinuous circular walls 44, 46. The inclined 40 nature of platform 40 will cause liquids to flow off readily, and staggered openings 48, 50 are provided in the spaced concentric walls 44, 46 respectively, to keep any fluids from collecting on the platform. Shaft 30 is formed of such length that when it is disposed within casing 12, the central stud 20 fits into and is received within the bottom end of bore 32, and when the cover 14 is placed in position on the casing wall 13, the funnel walls 23, 25 interfit with the platform walls 44, 46 to form a light-tight closure which permits the free and uninterrupted flow of fluids into the interior of the casing. An opening 45 may be provided at the outer margin of cover 14, to function as an air vent and as an overflow flow and pouring passage.

Shaft 30, below platform 40, is substantially circular in cross-section, but is flattened on one side, as 52. The flattening extends from the bottom of shaft 30 to below platform 40. A plurality of horizontal recesses, as grooves 54, are

formed on shaft 30, across the flat side 52, although they need not be. A number of circular film discs 60 are provided, having central openings 62 adapted to receive shaft 30 therewithin. Central raised hub portions 64 are provided on the discs 60 surrounding openings 62, which are symmetrically shaped with respect to the lower portion of shaft 30, except that openings 62 are slightly larger than the thickness of said shaft. Openings 62 are just large enough so that the discs 60 may slide easily up and down along the length of shaft 30 although they cannot turn thereon.

We provide means whereby each disc 60 may be secured to shaft 30 at any desired point thereon, so that the discs can be arranged to receive films of different widths. A relatively short strip 15 of spring metal, or other suitable material 68 is provided, and crimped or otherwise secured onto disc 60 against the flat portion 65 of the disc opening. The center of the strip 68 is treated to provide a tongue or projection 72 which may extend entirely across the spring strip. Suitable recesses 69 are provided on the tops of the hub portions, and the ends 70 of the strips 68 are bent over to secure the spring strips 68 to the discs 60.

As shown in Fig. 4, the pressure normally exerted by the tension of spring strips 68, bearing against the shaft 30, with the spring tongue 72 fitting within the shaft recess 54, will serve to securely key the disc to the shaft. If it is desired to shift the disc along to the next space, or remove same from the shaft entirely, the disc is pressed against the shaft in the direction of the arrow, Fig. 4. The pressure will reduce the normal extension of tongue 72, so that the disc may be readily moved out of engagement with the particular recess and shifted as desired.

Discs 60 are provided with the usual film receiving grooves 80, and two or more discs may be used, as indicated in the Fink Patent No. 2,151,907, to receive one or more rolls of film within the tank during the processing operations.

With our new arrangement, the receptacle may be filled with and emptied of the processing fluids very quickly, thus making for more uniform development. The shaft bore 32 surrounding stud 20 loosely, enables the reel as a whole to be rotated freely by manual actuation at upper portion 34 projecting out of cover 14. The level of platform 40 is below the top of the casing wall 13, as shown, and the mouth of the funnel portion interfits with platform 40. With this arrangement, agitation can be secured without any special accessories and there is no danger of any light flashes fogging the film.

The circular bore 32 of shaft 30 enables the user to determine the temperature of the tank contents easily by inserting a thermometer thereinto, and the tapered top 34 of shaft 30 facilitates the washing step in the film processing since a rubber hose or tube can easily be secured thereon to direct a flow of water down the bore 32 and outwardly from stud 20, wall 22, and up through the openings 90 in the film discs 60. The outer surface of shaft top 34 may be knurled, to provide a grip for rotating the shaft. The centrifugal force of the rotation will operate to cause all fluids poured through funnel 19 to flow 70 into the receptacle. As above stated, however,

platform 40 is inclined downwardly to provide proper drainage in the absence of rotation.

All the components of our tank can be formed easily and relatively inexpensively. They can be made either of Bakelite, synthetic plastics, stainless steel, etc., but our preferred embodiment, as illustrated, is made of Bakelite.

Having now described our invention, what we claim and desire to secure by Letters Patent is:

1. A film processing tank comprising a casing, a cover therefor provided with a downwardly extending funnel, an annular flange defining the mouth of the funnel, and a film supporting reel disposed within the casing comprising a shaft, having an outwardly extending platform formed thereon, annular upwardly extending concentric walls on the platforms, the funnel flange interfitting with certain of the platform walls in light tight relationship.

2. A film processing tank comprising a casing, a cover therefor provided on the underside thereof with a pair of concentric spaced apart downwardly extending annular walls, a passageway through the center of the cover, and a film supporting reel disposed within the casing comprising a shaft having an outwardly extending platform thereon, the platform having thereon a pair of upwardly extending, concentric and spaced apart annular walls interfitting with the cover walls.

3. A film supporting reel for use in a film processing tank comprising a casing and a centrally apertured cover therefor, the reel comprising an elongated shaft the upper part of which is adapted to project upwardly of the tank and through the apertured cover, and the lower part of which extends into the tank, an outwardly extending platform separating the upper and lower portions and interfitting with the cover in light-tight relationship, a plurality of recesses in said lower portion, a plurality of circular discs, an opening in each of said discs to receive therethrough the lower portion of the shaft, which opening in each of the discs corresponds in shape to the shape of the lower portion of the shaft and is surrounded by a hub portion, and means on each of said discs secured to said hubs to removably engage the shaft recesses which means comprise a spring crimped to said hub portion of each disc, having a projection to removably fit the shaft recesses, whereby to secure the discs to the lower portion of the shaft at any desired point thereon between the end and the platform.

4. In a film processing tank, a casing, a centrally apertured cover therefor, and a device for supporting film for processing within the casing, the device comprising an elongated shaft having a platform formed integrally therewith and projecting outwardly therefrom, a portion of the shaft above the platform projecting upwardly through the apertured cover and the shaft below the platform extending into the casing, and a plurality of centrally apertured discs removably keyed onto the lower portion of the shaft from the bottom of the shaft, the apertures in the discs being smaller than the diameter of the platform, and the platform and cover interfitting in light-tight relationship.
